(57) **CLAIM**

The ornamental design for a watch dial, as shown and described.

DESCRIPTION

FIG. 1 is a perspective view of a watch dial showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dashed broken lines depict environmental subject matter that form no part of the claimed design. The dash-dot-dash broken lines define the bounds of the claimed and form no part thereof.

1 Claim, 5 Drawing Sheets(56)
